United States Patent

Des. 240,832
Patented Aug. 3, 1976

240,832

CALCULATING MACHINE

Myron Beitler, West Orange, and Terry L. Barner, Morris Plains, N.J., assignors to Litton Business Systems, Inc.

Filed Apr. 3, 1975, Ser. No. 564,743

Term of patent 14 years

Int. Cl. D18—01

U.S. Cl. D26—5 C

FIG. 1

FIG. 2

FIG. 3**FIG. 4**FIG. 1 is a perspective view of a calculating machine showing our new design;

FIG. 2 is a right side elevational view thereof, the left side being a mirror image of the right side shown;

FIG. 3 is a top plan view thereof; and

FIG. 4 is a rear elevational view thereof.

We claim:

The ornamental design for a calculating machine, as shown and described.
